UNITED STATES PATENT OFFICE.

HARRY E. CHRISTENSEN AND JOHN L. LOEHNIS, OF SAN FRANCISCO, CALIFORNIA;
SAID LOEHNIS ASSIGNOR TO SAID CHRISTENSEN.

AUTOMATIC STOP DEVICE FOR AUTOMOBILES.

Application filed April 26, 1926. Serial No. 104,857.

This invention relates to an impact actuated stop mechanism for motor vehicles and the like, whereby a vehicle is automatically brought to a stop after collision with another vehicle, a pedestrian or the like.

The object of the present invention is to generally improve and simplify the construction and operation of devices of the character described; to provide a mechanism which may be actuated either by the bumper or the fenders of a vehicle, and which is so constructed that it is adapted to close off the flow of gas from the carburetor to the motor and thereby bring the vehicle to a stop.

The invention more specifically stated embodies a stop valve interposed between the carburetor and the inlet manifold of a motor, and means connected with the bumper and the fenders whereby the valve is automatically closed and the motor stopped when another vehicle, a pedestrian or the like is struck by the bumper or fenders.

The invention is shown by way of illustration in the accompanying drawings, in which—

Fig. 1 is a perspective view of the front end of a motor vehicle showing the application of the invention.

Fig. 2 is a central, longitudinal section of a part of the mechanism, showing it connected with the carburetor of a motor vehicle.

Fig. 3 is a perspective view of a part of the mechanism which will hereinafter be described.

Referring to the drawings in detail, and particularly to Figs. 1, 2 and 3, A indicates the main frame of a motor vehicle, B the motor, C the carburetor, and D the inlet manifold. The carburetor is more particularly shown in Fig. 2. By referring to this figure it will be noted that it is provided with an ordinary throttle valve control, such as indicated at 2, and it will further be noted that it is provided with a secondary throttle valve indicated by dotted lines at 3. This secondary throttle valve will hereinafter be referred to as the stop valve and its function will also be later described.

The valve 3, like the throttle valve, is an ordinary type of butterfly valve. It is mounted on a shaft 4 and this shaft is provided with a crank arm 5 which in turn is connected with a link 6. The stop valve 3 is interposed between the carburetor and the

inlet manifold, as shown, and it serves the function of completely cutting off the gas supply to the manifold and the motor when thrown into operation.

By referring to Fig. 1 it will be noted that the frame is provided with an ordinary bumper E and the usual type of front wheel fenders, as indicated at F.

The purpose of the present invention, as briefly stated in the preamble, is to provide a mechanism whereby the stop valve 3 is automatically thrown to closed position when an object is encountered or struck with sufficient force to cause deflection or bending of the fenders or the bumper. This mechanism will now be described.

By referring to Figs. 2 and 3, it will be noted that a bracket member G is employed, this being supported adjacent the carburetor by means of a plate or the like as indicated at 7. The member G is angle-shaped. Its upper surface is provided with a plurality of channels or grooves, as indicated at 8, and similar grooves 9 are formed in the rear surface. Slidably mounted in the upper grooves 8 are latching members 10. There is one latch in each groove and as they are all identical in shape and construction a brief description of one should suffice.

By referring to Fig. 2 it will be noted that the latch consists of an elongated bar which terminates in a hook member 11. It is provided with an upturned lug 12, adjacent the hook, and the opposite end is perforated as at 13 to receive a cable or link 14. A cover member 15 is secured to the upper face of the bracket member G and the latch members are thus held against accidental removal. The forward end of the cover carries lugs 16 which extend down into the respective grooves 8. Springs 17 are interposed between the lugs 16 and 12 of the respective latches and the tension of the springs is such as to normally force the latches in the direction of arrows a. The latches are, however, held against such movement by means of the cables 14. Two of the cables, such as indicated at 14^a and 14^b, are attached to opposite ends of the bumpers and the other two cables indicated at 14^c and 14^d are attached to the outer ends of the front fenders, suitable guide pulleys such as indicated at 18, 19 and 20 being employed to guide the cables to their respective points. The cables are permanently at

tached at their outer ends to the respective members, such as the bumpers and the fenders, and they accordingly hold the latches 10 against the tension of the springs 17.

5 It was already stated that the rear face of the bracket member G was also grooved, as indicated at 9. These grooves also contain latches, generally indicated at 21. These latches are also identical in construction 10 and function and the description of one should suffice. These latches are elongated bars, as shown in Fig. 2. Their upper ends are bent at right angles as at 22 and are engaged by the hook-shaped ends 11 15 of the latches 10. Each latch member 21 is provided with a lug 23 and the latches are retained against removal in the grooves by means of a cover plate 24. The upper end of this cover plate carries lugs 25 which 20 extend into the respective grooves and helical compression springs 26 are placed in the respective grooves between the lugs 23 and 25, and the tendency is, therefore, to push the latches 21 downwardly in the grooves in 25 the direction of arrow b.

The link 6, which is connected to the crank arm 5 of the stop valve 3, is normally held in elevated position where valve 3 is completely opened by means of a spring or the like, such as indicated at 27. The lower end of the link carries a bucket-shaped member 28. This bucket-shaped member is disposed below the lower ends of the latches 21, so that if one or more of the latches 21 are 30 released and forced downwardly by means of the tension of the springs 26, a downward movement will be transmitted to the link 6 and the crank arm 5 will thus be rocked to swing the valve 3 to closed position. The latches 10 and 21 have a limited movement 35 as the inner end of the cover plate 15 is provided with a downturned flange 15^a which engages the lugs 12 and thereby limits the movement of the latches 10. The lower end of the cover member 24 is similarly provided with an inturned flange 24^a and this 40 limits the downward movement of the latches 21. The movement transmitted to the latches 10 is, however, sufficient to bring the hook-shaped members out of engagement 45 with the upper ends 22 of the latches 21, so that the latches 21 may be released and projected in a downward direction by the springs 26. The downward movement of 50 the latches 21 is in turn sufficient to impart the proper movement to the link 6 and the crank arm 5 or, in other words, sufficient movement to permit complete closing of the stop valve 3.

55 The main purpose of the present invention is to stop reckless drivers from escaping when they have been the cause of an accident. Such drivers are usually referred to as "hit and run", "slautoists", etc., and 60 if automobiles were all equipped with a de-

vice such as here shown, drivers of that character would never escape.

To clearly prove the statement, let us consider that a careless driver strikes another machine, for instance, with the bumper E. 70 The impact under such conditions should be sufficient to cause compression of the bumper or bending thereof. This causes either of the cables 14^a or 14^b, or both, to slacken and springs 17 will thus be permitted to exert 75 their pressure to move the latches 10 rearwardly a sufficient distance to release the latches 21. These in turn when released strike the bottom of the bucket 28 and thereby pull the link 6 in a downward direction 80 and causes complete closing of the valve 3. The gas supply from the carburetor to the motor is thus completely cut off and the motor and the vehicle will come to a stop. A would be "hit and run" driver will thus 85 be prevented from escaping, as it would take sometime to re-set the latches so as to permit opening of the stop valve 3. If the impact during the collision were severe, the fender or the bumper would be so badly 90 bent that it would be almost impossible to straighten them sufficiently to permit the latches to be returned to normal interlocking position, and so much time would at least be lost if the driver should try to escape that the injured party or witnesses 95 would have an opportunity to get the number of the machine, etc.

If a careless driver should strike another machine or a pedestrian with one of the fenders only, the fender would bend inwardly and the slack in the cable connected therewith would become sufficient to release one of a cooperating set of latches 10 and 21. The vehicle would accordingly be brought 100 to a stop if an object were hit with either fender, or by either end of the bumper or by the bumper as a whole, and the careless driver would have a comparatively small 105 chance of escaping, as the motor would become dead and the vehicle would be brought 110 to a complete stop in any instance.

In the present instance we have shown the device as attached to the front bumper and fenders only. It is obvious that it may be attached to a rear bumper and fender if desired, as it would also in that instance 115 serve a useful function. For instance, it has often been observed that a driver in turning out from the sidewalk, where several 120 cars are parked in line, usually must back up and then go ahead one or more times before the front wheels of his vehicle will clear the vehicle in front. Under such conditions a driver often has a tendency to back 125 into the car in back of him and may damage its fenders, headlights, etc. If he should back into another car while equipped with the mechanism here shown, his own car 130 would be stopped and knowing this he would 135

be exceedingly careful in backing up, thereby avoiding damage to other cars.

Having thus described our invention, what we claim and desire to secure by Letters

5 Patent is—

1. The combination with a carburetor and a motor, of a motor driven vehicle, of a valve interposed between the carburetor and the motor, a plurality of plunger members,

10 anyone of which is adapted to close the valve, a plurality of latches normally maintaining the plungers in a position where the valve may remain open, a pair of fenders and a bumper on the vehicle, a connection

15 between each latch and the fenders and bumper, said connections normally maintaining the latches in locking engagement with the plungers, said means also releasing one or more of the latches when the vehicle

20 strikes an object with sufficient impact to bend the fenders or the bumper, thereby releasing one or more of the plungers and closing the valve.

2. The combination with the carbureter and motor of a motor driven vehicle, of a valve interposed between the carbureter and the motor, means normally maintaining said valve in an open position, fenders on the vehicle, a bumper on the vehicle, a latch-

25 supporting housing positioned adjacent the valve, a latch in said housing, a connection between the latch and the valve, means normally maintaining the latch in a retracted position and the valve in an open position, and means whereby the latch is automatically projected and the valve closed when the vehicle strikes an object with sufficient impact to bend the fenders or the bumper.

3. The combination with the carbureter and motor of a motor driven vehicle, of a valve interposed between the carbureter and the motor, means normally maintaining said

valve in an open position, fenders on the vehicle, a bumper on the vehicle, a latch-supporting housing positioned adjacent the 45 valve, a plurality of latches mounted in said housing, a connection between the latches and the valve, a flexible connection between each latch, the bumper and the fenders, normally maintaining the latches in a retracted 50 position and the valve in an open position, and means whereby one or more of the latches are automatically projected and the valve closed when the vehicle strikes an object with sufficient impact to bend the 55 fenders or the bumper.

4. The combination with the carbureter and motor of a motor driven vehicle, of a valve interposed between the carbureter and the motor, means normally maintaining said 60 valve in an open position, fenders on the vehicle, a bumper on the vehicle, a latch-supporting housing positioned adjacent the valve, a plurality of latches mounted in said housing, a flexible connection between each 65 latch, the bumper and the fenders normally maintaining the latches in a retracted position, a plurality of secondary latches also mounted in the housing and normally maintained in a retracted position by means of 70 the first-named latches, a crank arm on the valve, a link connected therewith, a bucket on the link disposed in alignment with the secondary latches, and means whereby one or more of the first-named latches are automatically projected to release one or more of the secondary latches when the vehicle strikes an object with sufficient impact to 75 bend the fenders or the bumper, said secondary latches when released engaging the 80 bucket and imparting a movement to the link to close the valve.
